VEHICULAR TOY OR SIMILAR ARTICLE

Jarvis W. Rockwell, Chicago, Ill., assignor to Playskool
Manufacturing Company, Chicago, Ill., a corporation
of Illinois

Filed July 5, 1966, Ser. No. 2,941

Term of patent 14 years

(Cl. D34—15)

Fig. 2

FIGURE 1 is a side elevational view of the vehicular toy showing my new design;

FIGURE 2 is a top plan view;

FIGURE 3 is a front elevational view;

FIGURE 4 is a rear elevational view; and

FIGURE 5 is a perspective view of the vehicular toy of my design, wherein the undercarriage thereof, as well as the broken line showing of the reins, are omitted.

The dominant features of the design reside in the portions shown in full lines.

The characteristic feature of my design resides in a normally horizontal seat portion supported on downwardly diverging pairs of legs and having upwardly diverging backrest and handle portions, presenting the general appearance of a horse or the like, all as shown.

I claim:

The ornamental design for a vehicular toy or similar article, as shown and described.
